UNITED STATES PATENT OFFICE.

GEORGE W. JORDAN, OF STEUBENVILLE, OHIO.

JOURNAL-LUBRICATING DEVICE.

Application filed December 24, 1923. Serial No. 682,449.

To all whom it may concern:

Be it known that I, GEORGE W. JORDAN, a citizen of the United States of America, and resident of Steubenville, county of Jefferson, 5 and State of Ohio, have invented certain new and useful Improvements in Journal-Lubricating Devices, of which the following is a specification.

This invention relates broadly to lubricating mechanisms, and more specifically to 10 apparatus for feeding grease to the necks of rolls.

The primary object of the invention is to provide a force feed mechanism for furnishing 15 to roll bearings, or to the necks or journals of rolls, as the rolls of a rolling mill, a constant supply of the heavy grease required for effecting proper lubrication.

In describing the invention in detail, reference 20 is herein had to the accompanying drawings, in which—

Figure 1 is a side elevation of the invention mounted upon a rolling mill housing;

Figure 2 is a view of the same, partly in 25 elevation and partly in vertical section, taken at a point at a right angle to the view-point in Fig. 1; and

Figure 3 is an enlarged horizontal sectional elevation of a portion of the gearing 30 which includes one member of the clutch and the crank arm.

Referring to said drawings, 1 indicates the upper roll of a set of rolling mill rolls, and 2 a housing of such mill. Mounted upon 35 the housing 2 are suitable supports, as the brackets 3 and 4, by which is carried an upright casing-like container 5 for grease which is to be supplied to the adjacent neck 1^a of said roll 1. Said container is preferably of inverted conical, or funnel, form and has a wide hopper-like mouth portion 6 at its upper end. Journaled in suitable bearings within said container is a central vertical shaft 7 which carries a spiral blade 8 of 40 screw propeller type, by means of which grease introduced within said container is impelled from the lower end of the latter, as through a laterally disposed spout 9 which overhangs said roll neck.

While the bearings for the shaft 7 may be otherwise arranged, it is preferred that a bearing-plate, as 10, be suitably disposed in or at the lower end of the container 5 and that a horizontal cross bar 11 be detachably mounted upon the hopper 6, said bar carry-

ing a bearing 12 for the upper end of the shaft.

Secured on the upper end portion of the shaft 7, as by a set screw 13, is a sleeve 14 which carries a bevel gear 15; and disposed 60 in operative driving relation to said gear is a similar gear or pinion 16 carried by the inner section of a horizontal shaft 17 which is journaled in suitable bearings 18 and 19 formed on or carried by the housing-carried bracket 4 or other suitable support. The outer section of said shaft 17 has keyed 65 upon its outer end a crank arm 20 which carries on its outer end a crank pin 21, and mounted pivotally on said pin is a sleeve 70 block 22 which has extended lengthwise therethrough and shiftable therein the upper end portion of an eccentric rod 23. Said rod is carried by an eccentric sleeve 24 within the embrace of which is rotatable an eccentric 75 25 that is mounted on a suitable rotating part of the mill, as upon the coupling 26 which operatively connects the adjacent wobblers 27 of aligned rolls of a roll train. Springs 28 and 29 interposed, respectively, 80 between the sleeve block and fixed collars 30 and 31 carried by said rod are designed to relieve back-lash.

A suitable clutch mechanism whereby the sections of the shaft 17 may be operatively 85 connected and disconnected is provided, the clutch 32 herein shown being of a common type in which the shiftable member is moved by means of a hand lever 33.

Disposed for rotation with the shaft is 90 one or more radial arms 34, herein shown as carried by the sleeve 14, and carried by said arms are blades or scrapers 35 designed to be rotated within the hopper 6, close to the hopper walls for stirring or agitating the 95 grease in said hopper to cause it to feed downward within the casing to a level at which it will be caught by the revolving spiral blade 8.

While I have herein disclosed by invention in what I consider to be its simplest practical form, it will be manifest that various changes in the details of construction and arrangement may be resorted to without departing from the spirit of the invention as defined in the appended claims.

What is claimed is—

1. The combination with a set of rolling mill rolls and housings therefor, of mechanism for supplying lubricating grease to the 110

neck of the upper of said rolls, said mechanism being operative only during operation of said rolls and comprising a support mounted on the housings adjacent to said neck, a grease container mounted on said support, said container having a hopper-like mouth portion at its upper end and a delivery spout at its lower end, a shaft journaled centrally within said container, a propeller screw carried by said shaft within the body portion of said container for extruding grease through said spout upon said roll neck, blade-like agitators carried by said shaft within the hopper portion of the container, drive gearing for said shaft, and shiftable means whereby said gearing may be rendered either operative or inoperative.

2. The combination with a set of rolling mill rolls and housings therefor, of mechanism for supplying lubricating grease to the neck of the upper of said rolls, said mecha-

nism comprising a support mounted on the housings adjacent to said neck, a grease container mounted on said support, said container having a hopper-like mouth portion at its upper end and a delivery spout at its lower end, a shaft journaled centrally within said container, a propeller screw carried by said shaft within the body portion of said container for extruding grease through said spout upon said roll neck, blade-like agitators carried by said shaft within the hopper portion of the container, drive gearing for said shaft, and shiftable means whereby said gearing may be rendered either operative or inoperative.

In testimony whereof I affix my signature in presence of two subscribing witnesses.

GEORGE W. JORDAN.
